UNITED STATES PATENT OFFICE

2,326,914

BASIN UNIT

Leif Andersen, Chicago, Ill., assignor to The Pullman Company, Chicago, Ill., a corporation of Illinois

Original application July 31, 1940, Serial No. 348,670. Divided and this application November 28, 1949, Serial No. 367,600

17 Claims. (Cl. 4—169)

The present invention relates to a complete and extremely compact wash basin unit of standard height above the floor when in its operative position and yet one which may be folded into a small space. Complete faucet equipment is provided, including hot and cold water faucets, a liquid or powdered soap dispenser and a dental faucet, all of which are assembled in a compact casing directly above the basin. The casing has a cover, which when closed makes the faucets and soap dispenser inaccessible to the public. The basin may be locked in its inoperative position and when so disposed, the faucet assembly also is locked so that it too is rendered inaccessible.

The equipment disclosed herein is particularly well suited for use in railway passenger cars and is shown in a relatively new type of accommodation known as a "Coach sleeper." This type of sleeping car accommodation has just recently been introduced to the traveling public.

Toilet stands per se have been employed in vehicles for sometime, but their use always has presented a problem confronting engineers when they are arranging the floor plan of the car and designing the spacing of the windows. The toilet facilities heretofore employed have required considerable wall and floor space even when folded into their inoperative position.

The basin disclosed herein when closed is entirely below the window height so that only a relatively narrow blank wall area between the windows need be provided, just sufficient to accommodate the small faucet unit and a narrow mirror. The required floor space to accommodate these facilities is reduced to a minimum. This feature is important because wall and floor space are scarce and it is important to arrange the area to save as much as possible for the use of the occupants.

The present invention overcomes all of the objections enumerated above and, in addition, provides a simple and inexpensive basin and faucet arrangement of ample size for general use and one which is extremely simple to manipulate.

The above constitutes some of the principal objects and advantages of the present invention, others of which will become apparent from the following description, in which

Fig. 1 is a plan view of about one-half of a car showing the present invention in its relationship with the other equipment of the car;

Fig. 2 is a plan view of the other half of the portion of the car shown in Fig. 1;

Fig. 3 is a fragmentary perspective view of the car showing a three and a six passenger room made up for day use;

Fig. 4 is an enlarged front elevational view of the folding wash stand forming the subject matter of the present invention showing the stand in its closed position with the faucet unit covered, a portion of the housing closing the basin being broken away to show the track and follower member which guide the basin in its movements in and out of the housing;

Fig. 5 is a vertical sectional view through the folding wash stand taken on the line 5—5 of Fig. 4;

Fig. 6 is an enlarged detail sectional view showing the cooperation between the basin and the faucet cover when both are in their closed position;

Fig. 7 is an enlarged detail view taken on the line 7—7 of Fig. 5;

Fig. 8 is an enlarged vertical sectional view through the wash stand showing the wash basin in solid lines in its operative position with the dental faucet in the "on" position and indicating in broken lines the basin in its vertical position about to be lowered into the basin housing to its inoperative position;

Fig. 9 is an enlarged perspective view of the basin assembly including the faucet unit and showing the basin and faucet unit in their operative position;

Fig. 10 is a side view of the faucet casing and pivoted cover member showing the spring assembly holding the cover in open and closed positions;

Fig. 11 is an enlarged horizontal detail sectional view through the wash stand with the basin shown in its closed position taken on the line 11—11 of Fig. 5;

Fig. 12 is an enlarged detail sectional view through the wash stand taken on the line 12—12 of Fig. 5; and

Fig. 13 is an enlarged detail view of the dental faucet valve shown in Fig. 4 with the valve portion shown in vertical section.

This application is a division of the co-pending application of Peter Parke, James K. Tully, Leif Andersen and Basil E. Jones, Serial No. 348,670, filed July 31, 1940.

A specific embodiment of the present invention is selected for the purpose of disclosure as required by Section 4883 of the Revised Statutes. Many modifications may be made without departing from the scope of the invention.

GENERAL ORGANIZATION

Car body arrangement

The invention is shown applied to a particular type of sleeping car known as a "Coach-Sleeper." Referring to Figs. 1-3, inclusive, the car body 50 is shown having a floor 51 (Fig. 3), a pair of sides 52 and 53, and a roof 54. No attempt has been made to show the underframe and trucks or any structural details of the car framing.

Referring to Figs. 1 and 2, an aisle 55 extends the full length of the car adjacent to car side 52, and at each end of the car is a passageway door 56 leading from the aisle onto the platform 58, in the case of one end of the car, or onto the treadplate (not shown) between coupled cars at the other car end. The vestibule 58 is provided with doors 59 which open to the outside of the car and the usual trap doors 60 cover steps leading down from the vestibule platform. A passageway opening (not shown) in the car end wall gives access to and from the adjoining car.

The floor plan arrangement of the car includes a plurality of three and six-occupant rooms, referred to at "A" and "B", respectively, spaced throughout the greater portion of the car length and placed adjacent to the car side wall 53. At the opposite ends of the car are toilet facilities intended for use by the men and women, respectively, occupying the car, the men's facilities being indicated at 64, and the women's at 65. The men's facilities include a small room 66 equipped with a hopper 67, a door 68 closing this room from the aisle and two lavatories 69 and 70, separated from each other by a partition 71, and each closed from the aisle by a curtain 72. Each lavatory is provided with a wash basin 73.

At the opposite end of the car, the women's facilities include a small room 74 provided with a hopper 75. A door 76 closes this room from the aisle. Two lavatories 77 and 78 are placed adjacent to room 74, and each is provided with a wash basin 79. A folding partition 80 separates each of the lavatories from the aisle. Locker space and equipment cabinets, generally indicated at 110 and 111, are placed at the opposite ends of the car. A portion 112 of the storage space 111 serves as a baggage storage compartment, and a door 113 opening from the outside of the car provides access into this storage space.

In the car side wall 52 are windows 81, and in the wall 53 windows 82 are located to give proper lighting to the rooms and to provide the passengers with suitable window areas.

Fastened to the side wall 52 of the car at each side post is a folding seat 83, which is normally held by a spring against the wall, but which can be pivoted to a horizontal position for use as a seat.

General room arrangement

Adjoining rooms are separated from each other by a partition 84 which extends from the car side wall 53 across the car to an aisle partition 85. A part of the partition 84 is cut away at 86 (Fig. 3) over the sofa back so that a view throughout the entire car length can be had. A curtain 87 is snap fastened or otherwise secured to the partition 84 over the opening 86, thus closing the opening. The partition 85 is cut away at 88 (Fig. 3) adjacent to the end of each

sofa, and an upholstered arm rest 89 is provided on the lower horizontal portion of each partition. Each of the end rooms in the car is closed from the aisle by a partition 86.

3 The rooms A, adapted to accommodate three occupants, are equipped with a convertible sofa 87 adapted to form a lower berth (Figs. 1 and 3), an upper berth or bunk 88, and an intermediate berth 89. Against the car side wall are toilet facilities, generally indicated at 90, above which is a mirror 91, a shelf 93, and a baggage rack 92. A soiled towel basket 94 is placed to one side of the toilet facilities. Each seat is provided with a foot rest 95 for each occupant. One or two 10 windows 82 per room, depending on the size of the room, are located in car side wall 53. At the opposite ends of the sofa are lighting fixtures 97 for furnishing illumination for the occupants when the room is made up for day use. At least 15 one similar berth light is provided for each of the intermediate and upper berths; and overhead lighting fixtures 98, 100, and 101 are situated on the ceiling of each room. Over each mirror 91 is a light 96 directing light downwardly. A plurality of lighting fixtures 107 is spaced throughout the length of the car over the aisle, and over each entrance to the vestibule 58 is a light 108. The lavatories and toilets for both the men and the women are provided with suitable lighting fixtures 109.

20 The six-occupant rooms B are similarly equipped, except that there are two convertible sofas 87 on opposite sides of the room facing toward the center (Fig. 1).

25 35

Washstand

In each of the rooms is a very compact and complete washstand 95 utilizing a minimum of space and yet of standard height when the wash 40 basin is in position for use. Referring to Figs. 3 and 9, the washstand includes a housing 445 supported on car wall 53 and enclosing numerous pipes and other equipment making up the washstand. A door 447 near the bottom of the housing 45 is hinged at 448 provides access into the housing interior to permit repairs to be made to the equipment inside the casing.

45 A basin 449 is supported on the housing 445, as will presently be described.

50 Directly above the basin a faucet assembly, generally indicated at 450, is carried in the car wall 53, and directly above the faucet assembly is the mirror 91.

The details of the washstand are shown in 55 Figs. 4, 5, 7, 8 and 10-12 inclusive. The front face of housing 446 is shown at 451 (Fig. 5), and the back face at 452 in Fig. 12. Housing sides 453 connect the front and back faces to completely enclose the equipment making up the washstand facilities.

60 On each of the side walls 453 of the housing 446 is a track 454 extending diagonally upwardly on the inner face of each side 453, and the top branches out in the form of a Y at 455 (shown 65 in Figs. 5 and 8).

The basin 449 comprises a bottom sheet 456 a pair of sides 457, a top plate 458, and a basin sheet 459 supported from the top plate 458 and extending downward to a point slightly above 70 the bottom sheet 456, as best shown in Fig. 12. The top sheet 458 of the basin has a circular opening at 460 (Fig. 12) to provide access into the basin proper, of which the basin sheet 459 forms the bottom. The top sheet 458 extends slightly over into the opening 460 and is bent

under at 461 to form a reinforced peripheral edge around the opening 460.

A front sheet 462 extends from the forward edge of the top sheet 458 (Fig. 5) to the bottom sheet 456 to close the front of the basin, while the other end of the basin is left open at 463. The basin sheet 459 is curved to form a lip 464 so that when the basin is tilted to the vertical position for emptying, water may be spilled over this lip. The top sheet 458 on the basin is bent inwardly at 465 at the open end 463 of the basin to further direct the water as it is being emptied from the basin.

Along each side 453 of the basin is secured an inwardly extending casing 466 (Figs. 7 and 12) having outwardly extending flanges 467 for attachment to the basin wall. Inside this casing is a follower member 468 adapted to ride in the track 454, and a thumb nut 469, threaded through a boss 470 on the outer face of the casing 466, is threaded into an opening 471 in the follower member 468. A washer 494 is inserted between the free end of the thumb nut and the follower 468. Coil springs 495, under initial compression and housed in slots 496, bear against the inner face of the casing 466, thereby properly centering the follower 468 in the track 454. The thumb nut 469 adjusts the position of the follower member 468 with respect to the casing 466 and the track 454. Spaced from the casing 466 on each side 457 of the basin is a second bracket of identical construction having a follower 472 held in track 454 in the same manner as previously described with respect to the follower 468.

When in its closed position, the basin 449 extends vertically as shown in Fig. 5, inside the housing 446 with the lower follower 472 against the bottom edge 473 of the track 454. A portion of the basin bottom 456 at 474 lies in the plane of the front face 451 of housing 446, so that, when the basin is closed, this portion of the bottom sheet, as well as the front sheet 462 of the basin, cooperates with the housing walls to completely enclose the washstand equipment.

As best shown in Fig. 5, a hand grasp member 475 is fastened to the face 474 of the basin. To place the basin in operative position, the operator grasps the member 475 and raises the basin so that the follower members 468 and 472 move upwardly in track 454. Due to the fact that this track extends diagonally away from the wall, the basin moves upwardly and slightly outwardly away from the wall. When the follower member 468 reaches the upper limit 476 of the track, the lower follower member 472 stands at the entrance to the arm 477 in the Y portion 455 of the track. Inasmuch as the upper portion 478 of the track has a horizontally extending portion 478 so that the upper follower member 468 can be rotated to a horizontal position, the basin is moved to the horizontal position, during which time the lower follower member 472 passes upwardly into the arm 477 of the track until it strikes the upper limit 479 of this portion of the track. When in its horizontal position, the basin is supported on the horizontal portion 479 of the track on each side of the basin. Inasmuch as the bulk of the weight of the basin extends outwardly beyond the front face 451 of the housing 426, the basin pivots about the horizontal portion 478 of the track, and the lower follower 472 is in the Y branch 477 of the track is limited in its upward movement by the upper limit 479 of the track. Referring to Fig. 8, the basin is shown in solid lines in its operative

position with the followers 468 and 472 in their positions at the upper extremity of the track.

To lower the basin into its inoperative position, the operator grasps the member 475 and rotates the basin about the pivot points at the follower members 468 in a counter-clockwise direction (Fig. 8) until the basin assumes the substantially vertical position shown in dotted lines 480 in Fig. 8. The basin is lowered, and, during this movement, due to the inclination in the track 454, it moves inwardly toward the wall until it reaches its lowermost position shown in Fig. 5.

A lock 559 is provided to permit locking of the basin in its closed position, and includes an arm 560 (Fig. 4) secured at its free end to the bolt 561 operating in a guide 562 and adapted to enter a slot 563 in the side wall of the basin housing. To remove the basin from the housing 446, the thumb nut 469 on each side of the basin is turned to move the follower 468 out of the track 454.

Inside the housing 446 is a liner housing 481 forming the drain into which the basin spills when it is tilted in a vertical direction. This housing includes a front wall 482 (Fig. 5) and a rear wall 483, which, as best shown in Fig. 11, is offset at 484 to provide a passage 485, through which piping is passed. Side walls 486 (Fig. 12) complete the four vertical walls of the housing. At the bottom of the housing 481, the front and rear walls 482 and 483 (Fig. 5), respectively, at their lower ends bend inwardly to form spillways 487 and 488, respectively, and a screen 489 closes the opening at the bottom of the spillways. The drain pipe 490 extends downwardly from the screen and empties through the floor of the car. A trap 491 (Fig. 4) is provided in the drain.

Referring to Fig. 4, bottom sheets 492 and 493 incline toward the drain pipe 490 and cooperate with spillways 487 and 488 to direct the water to the drain 490.

The back sheet 452 of the housing 446 and the rear wall 483 of the housing 481 at the upper extremities thereof are spaced to provide a passage 498, housing valve assemblies generally indicated at 499 in Fig. 5. A back sheet 452 along its upper edge is bent horizontally forward at 500, extending across the opening and bending down at 501 to form a downwardly extending flange slightly projecting over the plane of the rear sheet 483 of housing 481. In the enclosure sheet 500 is an opening 502, through which portions of the valve 499 project.

Referring particularly to Fig. 4, the valve assemblies 499 include the cold water faucet valve 503 and a hot water faucet valve 504, mounted on the cold and hot water pipes 505 and 506, respectively. These pipes 505 and 506 are attached to a source of cold and hot water, respectively, and a shut-off valve 505' regulates the flow of water through pipe 505, and shut-off valve 506' controls the flow of water through pipe 506. Extending upwardly from the cold and hot water valves are projecting members 507, in each of which a valve lever 508 operates (Fig. 5). Supported on the horizontal cover member 500 of the casing is a base supporting member 509, having an upper horizontal surface 510 spaced from the cover 500 in which is an opening 511, through which pass the projecting member 507 and the valve lever 508.

Again referring to Fig. 4, a third pipe 512 extends upwardly between the cold and hot water pipes 505 and 506, respectively, and this pipe at its lower end is connected to a supply of soap (not shown).

Faucet assembly

Directly above the wash basin 449 is a faucet unit, generally indicated at 450 in Fig. 5. This unit is adapted to be prefabricated and installed in the car as an assembly, and includes a casing 514 fitting into a recess in the car wall and having a curved back member 515 extending downwardly and having an inwardly extending flange 516, which rests on the upper surface 518 of the supporting member 508 and then projects downwardly at 519 at its lower edge. Across the top and along its two vertical sides, the curved back member 515 terminates in flanges 517, best shown in Figs. 4 and 5. These flanges are provided with holes 518 (Fig. 4) through which screws pass to secure the assembly to the wall. The casing 514 is open in front, so as to provide access to the faucets housed within the casing. A cover plate 520 (Figs. 5 and 8), having two inwardly extending sides 521, is pivoted to the casing 514 at 522, so that the cover plate 520 pivots about a horizontal axis through the pivot points 522 and may be rotated from the closed position shown in Fig. 5 to the open position shown in Fig. 8.

Referring to Fig. 10, the cover 520 is resiliently held in its open and closed positions by a spring assembly generally indicated at 523 on the outside of the casing 514. This assembly comprises a rod 524 rotatably mounted on a lug 525 extending outwardly from the side of the cover 520 through an arcuate slot 526 in the side of the casing. The free ends of rod 524 pass through a guide member 527 extending outwardly from the side of casing 514. Surrounding rod 524 between the guide member 527 and lug 525 is a coil spring 528, normally under compression. When the cover 520 is in its closed position, shown in solid lines in Fig. 10, the spring assembly 523 assumes the position shown in solid lines with lug 525 at the upper position in slot 526, and the force exerted by spring 524 against the guide member 527 and lug 525 holds the cover 520 in its closed position. When the cover 520 is rotated about its pivot points 522 to the open position shown in dotted lines in Fig. 10, the lug 525 moves in the arcuate slot 526 from the top position shown in dotted lines to the bottom position shown in broken lines, during which time the rod 524 moves transversely with respect to the guide 527, and the spring 528 compresses to permit the movement of the cover. As the lug 525 moves downwardly in the slot 526, it approaches a point midway in the slot in alignment with the guide member 527 and the cover pivot points 522, in which position the spring assembly 523 is in dead center, so that there is no tendency for the spring 528 to either open or close the cover 520. As the lug 525 continues in its downward movement in slot 526, it moves to a point below the dead center position to apply a force on the cover 520, tending to snap the cover to its open position. When the lug 525 reaches the lowermost position in the slot 526, the spring 528 is effective in maintaining the cover in this open position.

Extending downwardly from the lower edge of cover 520 is a flange 529, which serves as a lever which may be grasped for opening and closing the cover. When the cover is in its closed position shown in Fig. 5, the flange 529 projecting below the lower edge of the cover extends somewhat below the opening at the front of the faucet casing and laps over the downwardly extending flange 519 of the casing 514. The wash basin 449 closes against this downwardly extending flange

529, as best shown in Figs. 5 and 6, so that the cover 520 cannot be opened until the wash basin has been raised out of its casing 449.

The horizontally extending flange 516 of the casing back sheet 515 is open at 530 to permit passage therethrough of the upwardly extending members 507 of the faucets. Mounted on the horizontal flange 516 of the casing 514 is a faucet base 531 having an upwardly extending flange 532 resting against the rear wall of casing 514. Mounted on this base are hot and cold water faucet levers 533 and 534 respectively (Fig. 4), fulcrumed at 535 (Fig. 5), each having an arm 536 adapted to engage the valve lever 508. The faucet levers 533 and 534 are spaced apart, as shown in Fig. 4, and a soap dispenser 537 is mounted between the levers on the base 531. Water flows out of passage 513 (Figs. 4, 5 and 8) into the basin.

The soap dispenser 537 per se forms no part of the present invention, and consequently it is only generally shown to include the dispenser body 538 having a spout 540 and a plunger 541.

Mounted on the base 531 alongside the hot and cold water faucet lever assemblies is a gooseneck shaped dental faucet spout indicated at 542 in Figs. 4, 5, and 8. This faucet is fastened at its lower end to a dental faucet valve 543, best shown in Figs. 4 and 13. This valve is attached to the cold water faucet valve 504, and comprises a valve housing 544 having a water passage 545 communicating with the water passage in valve 504. Extending downwardly into the housing 544 is a rotary valve member 546 into which extends the passage 547 of the faucet 542. A horizontal passage 548 extends from the passage 547 in the rotary valve member 546 radially to the periphery of the rotary member. When the valve 543 is turned to its "on" position, the passage 548 in the rotary member 546 is in direct alignment with passage 545 in the valve casing 544, so that in this position water flows from the cool water valve 504 through passage 545 and 548 into passage 547, and thence upwardly through the dental faucet spout 542 to be discharged from the mouth 549 of the dental faucet (see Fig. 8). When the dental faucet is turned to its closed position shown in dotted lines in Fig. 4, the passage 548 in the rotary member 546 moves out of alignment with the passage 545 in the casing 544, thereby shutting off the flow of water through the dental faucet.

The valve casing 544 is cut away at 550 (Fig. 13) adjacent to the top thereof, and a lug 551 projecting outwardly from the rotary valve member 546, operates in this cut-away portion to limit the movement of the dental faucet spout 542. As shown in Fig. 4, this lug 551 strikes the casing 544 at 552 when the dental faucet is in its closed position, and, as shown in Fig. 13, lug 551 strikes the casing 544 at 553 when the faucet is in its "on" position. The rotation of the dental faucet spout 542 from the "off" position, shown in dotted lines in Fig. 4, to the "on" position shown in solid lines in Fig. 8, controls the flow of water through the spout.

The ports 545 and 548 in the valve housing 544 and the rotary valve member 546, respectively, are so arranged that the actual control of the flow of water through the dental faucet spout takes place during the latter part of the swing of the spout when it is approximately in its "on" position. Thus, when the spout is swung outwardly to the "on" position, the water commences to flow when the spout is almost at its full "on"

position over the basin; and, as the spout is swung in toward the casing, the water is turned off shortly after the spout leaves its full "on" position and while it is still over the basin.

The rotary valve member 546 extends downwardly below the bottom of casing 544, and a lug 554 projects outwardly from this extended portion of the rotary member. A coil compression spring 555 is inserted between the lug 554 and the bottom of casing 544, and this spring, being normally under compression, constantly urges the rotary valve member 546 downwardly into the casing 544. Adjacent to the lower end of the downwardly projecting portion of rotary valve member 546 is a pin 556, to which is attached a tension spring 557 anchored to the casing of the hot water faucet 503 at 558 (see Fig. 4). This spring constantly urges the dental faucet spout 542 to its "off" position shown in dotted lines in Fig. 4 so that, when the spout 542 is rotated to its "on" position, the spring 557 constantly urges the spout back to its "off" position.

Above each faucet assembly is a light switch panel 564 (Fig. 3) on which are mounted the switches for controlling the overhead lights, the electrical outlet for electric razors, porter bell, etc. The mirror 91 in each room is located directly above the light switch panel.

It is to be noted that a wash basin assembly is below the level of the lower edge of the window, both when the basin is closed and in its open position. The spacing of the windows then, is in no way affected by the width of the wash basin and, in the particular embodiment shown, the wall area between the windows in the six-occupant rooms need be only wide enough to accommodate the faucet assembly generally indicated at 450 in Fig. 3 and the mirror 91. Thus the windows can be placed properly to give the best possible view to the occupants of the seats.

The wash basin and faucet units are very compact and they are so arranged that the basin can be locked in its closed position which also makes the faucet unit inaccessible. This is the condition which will exist during the daytime in cars of the type described herein because it would be extremely unpleasant to the occupants of the seats nearest to the washstand to have other room occupants using the wash basin. These basins when used in the particular accommodation described herein, are primarily intended for use at night and in the morning during the time the room occupants are preparing for bed or dressing in the morning. The toilet facilities at the end of the car are always available to the room occupants and it is intended that these should be used during the daytime.

The key for locking and unlocking the wash basin is generally held by the porter in charge of the car, so that when the basin is locked in its closed position during the daytime, it cannot be opened and used by room occupants, unless the porter approves of such use.

I claim:

1. A normally horizontally disposed basin, a base for supporting the basin, pivot means for mounting the basin on the base, means associated with the basin and the base for providing vertical sliding of the basin with respect to the base so that the basin may be first tilted upwardly about its pivot points substantially to a vertical position over the base and then lowered vertically with respect to the base.

2. A wash basin supported on a wall in pivotal relationship about a horizontal axis adja-

cent to the rear edge of the basin, hot and cold water faucets supported by the wall directly above the basin and controlling the water flow into the basin, a movable cover plate adapted to cover the faucets to make them inaccessible, the basin being adapted to be pivoted upwardly against the wall over at least a portion of the cover plate, and means for locking the basin in this closed position.

10 3. A wash stand mounted on a wall comprising a basin normally assuming a horizontal position, means for pivoting the basin about a horizontal axis into a vertical position against the wall, a faucet assembly on the wall above the basin, a cover for the faucet assembly, horizontal pivot means about which the cover is moved to open and close the cover, the basin being adapted to close against the faucet cover when the latter is closed so that the cover cannot be opened until the basin is pivoted outwardly away from the wall, and locking means for holding the basin against the faucet cover.

4. A wash stand mounted on a wall comprising a basin normally assuming a horizontal position, means for pivoting the basin about a horizontal axis into a vertical position against the wall, a faucet assembly on the wall above the basin and comprising an outwardly opening casing in the wall, faucets in the casing, a cover adapted to close the opening in the casing, pivot means about which the cover is moved for opening and closing, the cover when closed together with the casing serving to completely enclose the faucets, the basin when in its vertical position against the wall cooperating with the cover when the latter is closed over the casing opening to prevent opening of the cover, and means for locking the basin in its vertical position against the wall.

5. A wash stand comprising an upwardly opening basin housing having front, rear, and side walls, a basin supported by the housing at the top thereof and disposed normally at right angles with the housing when in its operative position, means for tiltably and slidably mounting the basin on the housing so that the basin may be tilted into a vertical position above the housing and then lowered vertically into the housing, the basin when in its horizontal position having a front face which serves to close the top of the housing when the basin is in its lowered position in the housing.

6. A wash basin supported on a wall in pivotal relationship about a horizontal axis, a water faucet supported on the wall directly above the basin and adapted to discharge water into the basin when the latter is open for use, a movable cover plate pivoted about a horizontal axis and adapted to cover the faucet and a flange projecting beyond the lower edge of the cover when it is in its closed position, the basin being adapted to pivot upwardly against the wall and against the flange on the cover to maintain the cover in its closed position.

7. A faucet assembly comprising a bowl shaped casing open on one of its vertical sides, a faucet in the casing, a cover pivoted about a horizontal axis and adapted to close the open side of the casing, and a flange extending beyond the lower edge of the cover when in its closed position.

8. A wash basin normally assuming a horizontal position when in its operative position, a vertically opening casing adapted to receive the basin comprising spaced front and rear walls

connected by spaced side walls substantially at right angles to the front and rear walls, a substantially vertical track on the inner face of each side wall, a follower member on the basin operating in each track, and means at the upper extremity of each track cooperating with its corresponding follower to pivot the basin about a horizontal axis, the basin being adapted to be tilted into a vertical position above the casing and then lowered into the casing.

9. A wash basin normally assuming a horizontal position when in its operative position, a vertically opening casing adapted to receive the basin comprising spaced front and rear walls connected by spaced side walls substantially at right angles to the front and rear walls, a substantially vertical track on the inner face of each side wall having an outward inclination from the bottom to the top of the track, a follower member on the basin operating in each track, and means at the upper extremity of each track cooperating with its corresponding follower to pivot the basin about a horizontal axis, the basin being adapted to be tilted into a vertical position above the casing and then lowered into the casing.

10. A wash basin normally assuming a horizontal position when in its operative position, a vertically opening casing adapted to receive the basin comprising spaced front and rear walls connected by spaced side walls substantially at right angles to the front and rear walls, a substantially vertical track on the inner face of each side wall, a follower member on the basin operating in each track, means associated with the follower member for withdrawing the follower from the track so that the basin may be removed from the track, and means at the upper extremity of each track cooperating with its corresponding follower to pivot the basin about a horizontal axis, the basin being adapted to be tilted into a vertical position above the casing and then lowered into the casing.

11. A wash stand comprising a normally horizontal basin, a basin housing supporting the basin, a faucet assembly directly above the basin, the basin housing opening upwardly and comprising substantially vertical front, rear and side walls, a vertical track on each of the side walls, follower members on the basin riding in the tracks, means at the top of the track cooperating with the follower members for supporting the basin in a horizontal position, said last named means serving as horizontal pivot points about which the basin may be pivoted into a vertical position above the housing, the basin when in its vertical position being movable downwardly into the housing, a cover over the faucet assembly making the faucets inaccessible, the basin when lowered into the housing cooperating with the closed faucet cover to prevent opening of the latter, and means for locking the basin in the housing.

12. A wash stand unit comprising a normally horizontal basin movable into a vertical position, a basin housing opening upwardly and supporting the basin, the housing including front, rear, and side walls, a substantially vertical Y-shaped track on the inner face of each wall, a pair of followers on each side of the basin spaced longitudinally to the basin side and riding in the Y-shaped track, the basin in its closed position extending vertically in the housing with the followers on each side riding in the lower vertical portion of the Y, the basin being mov-

able upwardly out of the housing, the followers moving upwardly in the track until the upper follower reaches the upper extremity of one arm of the Y, the lower follower at this time assuming a position at the entrance to the other arm of the Y, and means at the top of the first mentioned arm of the Y for supporting the basin in a horizontal position and about which the upper follower may pivot to move the basin to the horizontal position, the lower follower moving upwardly in the second named arm of the Y during this pivoting movement of the basin, and means for supporting the basin in a horizontal position.

13. A washing stand comprising a basin and a basin support, means for pivotally mounting the basin on the support so that the basin may pivot from a horizontal operative position to a vertical inoperative position, the basin when in its horizontal operative position being disposed above the floor at a convenient height for use, vertical means associated with the basin pivot mounting means allowing the basin while in its vertical inoperative position to slide vertically downwardly on its support, and means for limiting the vertical movement of the basin.

14. In a room having a window in one of the room walls with its lower edge disposed above the floor, a basin support mounted against the wall below the lower edge of the window, a basin supported on the basin support, mounting means for the basin providing pivotal movement of the basin from horizontal operative position to vertical inoperative position, the basin when in its horizontal operative position being disposed at a convenient height for use, means associated with the basin support and basin mounting means providing vertical movement of the basin on the support only when the basin is in its vertical inoperative position so that the basin may be lowered with respect to the support to a position wherein the uppermost edge of the basin is disposed no higher above the floor than the lower edge of the window, and means for limiting this vertical movement of the basin.

15. A basin, a support for the basin including spaced vertical side members, one on each side of the basin, a substantially vertical track on each side member, a trunnion on each side of the basin cooperating with its corresponding track so that the basin may be moved substantially vertically with the trunnions moving in the tracks, means at the top of the tracks for supporting the basin in horizontal position, the basin being tiltable at the top of the track from its horizontal position to a vertical position and then adapted to be lowered to a relatively low, inoperative position.

16. A basin, a support for the basin including spaced, substantially vertical side members one on each side of the basin, an upwardly and forwardly extending track on each side member, a trunnion on each side of the basin cooperating with its corresponding track so that the basin may be moved up and down with the trunnions moving in the tracks, the positions of the tracks being such that the up and down movement of the basin is accompanied by relative, horizontal displacement, and means adjacent to the top of the tracks for supporting the basin in horizontal position, the basin being tiltable at the top of the track from the horizontal position and then adapted to be lowered to a relatively low, inoperative position.

17. A wash basin, a support for the basin, means for pivotally and slidably mounting the basin on the support so that the basin can pivot from a horizontal, operative position to a vertical, inoperative position, and then can be lowered relative to the support, a faucet assembly mounted above the basin including faucets and a cover member movable from an open position

exposing the faucets to a closed position covering the faucets and rendering them inaccessible, the basin when in its lowered inoperative position cooperating with the closed cover to prevent opening of the cover, and means for locking the basin in its inoperative position.

LEIF ANDERSEN.

CERTIFICATE OF CORRECTION.

Patent No. 2,326,914.

August 17, 1943.

LEIF ANDERSEN.

It is hereby certified that error appears in the printed specification of the above numbered patent requiring correction as follows: Page 3, first column, line 72, after "follower 472" strike out "is"; and that the said Letters Patent should be read with this correction therein that the same may conform to the record of the case in the Patent Office.

Signed and sealed this 5th day of October, A. D. 1943.

Henry Van Arsdale,

(Seal) Acting Commissioner of Patents.
